CLAIM

The ornamental design for a vent cover bracket, as shown and described.

DESCRIPTION

FIG. 1 is a top view of a vent cover bracket showing my new design, and where a bottom view is identical thereto;

FIG. 2 is a cross-sectional view thereof taken along line 2—2 in FIG. 1;

FIG. 3 is an end view thereof, and where an opposite end view is identical thereto; and,

FIG. 4 is a left side view thereof, and where a right side view is identical thereto.
